UNITED STATES PATENT OFFICE.

FREDRICK AUSER, OF SAN FRANCISCO, CALIFORNIA.

WATER-SAVING MINING-MACHINE.

SPECIFICATION forming part of Letters Patent No. 875,583, dated June 4, 1901.

Application filed May 31, 1900. Serial No. 18,498. (No model.)

To all whom it may concern:

Be it known that I, FREDRICK AUSER, a citizen of the United States, residing at San Francisco, in the county of San Francisco and State of California, have invented a new Water-Saving Mining-Machine, of which the following is a specification.

My invention is intended to be used in connection with the ordinary gold-saving sluice-box; and the objects of my invention are to receive all the gravel and water that passes through the sluice-box; second, to provide facilities for saving this water and at the same time carry off and dump the gravel; third, to return the water thus saved to a receptacle from which it can again be run through the sluice-box. I attain these objects by the mechanism illustrated in the accompanying drawings, in which—

Figure 1 is a longitudinal central section through the device. Fig. 2 is a transverse section on line $y-y$, Fig. 1.

Similar letters refer to similar parts throughout the two figures.

From the sluice-box D the water and gravel fall onto an endless belt A, which is securely fastened to two endless chains B. At regular distances riffles a are attached to the endless belt A. This endless belt and riffles are of sufficient width to travel along with the endless chains over the end drums b without any interference with the two side protectors c. These side protectors contain various apertures c of appropriate dimensions to allow exit of water that is being forced along by the endless belt and riffles and splashing against the side protectors. The water thus passing through the apertures c is kept within bounds by a protecting-cover G, made of heavy canvas or any material that will answer the

purpose and attached from the top of the side protectors c to the side frames E. The water flowing through the apertures and striking this covering is precipitated into box H, which is nothing more than the interior of the frame E. This frame is placed at a slight incline to allow the water confined to box H to run into tank F, from which it can be reused in the sluice-box D, first above mentioned. The apertures c are commenced in the side protectors C at a height sufficiently above the endless belt A to preclude the possibility of any of the gravel received from the sluice-box D making its exit with the water through said apertures. The gravel is carried along by means of the endless belt and riffles to a point on the end drum, where the chain, belt, and riffles commence their under movement or return journey, when the gravel must of necessity drop off from the belt, and, if so desired, can be taken by means of a chute to a more distant dumping-place.

What I claim as my invention, and desire to secure by Letters Patent, is—

The combination of a sluice-box and an endless traveling belt with riffles; side protectors with apertures, said side protectors having on their outsides covers to keep the water flowing through said apertures confined to box below—all in combination with means for saving water in a receptacle substantially as set forth.

In testimony whereof I have signed my name to this specification in the presence of two subscribing witnesses.

FREDRICK AUSER.
